UNITED STATES PATENT OFFICE.

EMILE HARDY, OF NEW YORK, N. Y., ASSIGNOR TO ANDREW H. HOAG, OF SAME PLACE.

DESIGN FOR A CLOCK-CASE.

SPECIFICATION forming part of Design No. 31,228, dated July 18, 1899.

Application filed June 13, 1899. Serial No. 720,414. Term of patent 3½ years.

To all whom it may concern:

Be it known that I, EMILE HARDY, a citizen of France, residing at New York, in the county and State of New York, have invented and produced a new and original Design for a Clock-Case, of which the following is a specification, reference being had to the accompanying drawing, forming part thereof and illustrating in front elevation a clock-case bearing and incorporating my design.

The leading feature of my design consists of the form and ornamental character of the clock-case, substantially as shown in the drawing.

15 In the drawing, A designates the clock-case as a whole, said case comprising the central ornamental band B, the ornate leg-supports C C, the representations of human figures D D, and the floral festoons E, all substantially as shown.

What I claim is—

The design for a clock-case, substantially as shown and described.

Signed at New York, in the county and State of New York, this 10th day of June, A. 25 D. 1899.

EMILE HARDY.
